FRONT PANEL FOR AN ELECTRIC HEATER

John C. Beckett, Kentfield, Calif., assignor to Wesix
Electric Heater Co., San Francisco, Calif., a corporation of California

Filed Oct. 1, 1959, Ser. No. 57,754

Term of patent 14 years

(Cl. D81—10)

FIGURE 1 is a perspective view of a front panel for an electric heater showing my new design.

It is to be understood that the grill pattern is shown in white lines and that said pattern, shown fragmentarily for convenience of illustration, is continuous throughout the entire area indicated.

I claim:

The ornamental design for a front panel for an electric heater, as shown and described.
